ALEX A. CLARKE, OF DALLAS, TEXAS.

WORK-ENGAGING SUPPORT FOR SURFACE-TREATING MACHINES.

1,366,633.

Specification of Letters Patent. Patented Jan. 25, 1921.

Application filed January 13, 1920. Serial No. 351,158.

To all whom it may concern:

Be it known that I, ALEX A. CLARKE, a citizen of the United States, residing at Dallas, in the county of Dallas and State of Texas, have invented certain new and useful Improvements in Work-Engaging Supports for Surface-Treating Machines, of which the following is a specification.

This invention relates to new and useful improvements in work engaging supports for surface treating machines.

This invention has particularly to do with surface treating machines involving a revolving surface treating member. The idea involved is to provide an adequate support both in advance of and following the revolving member whereby the machine is held steadily and evenly and the entire surface extending to the edges of the work, may be treated without variation in finish or deviation in depth of cut. It is obvious that the work of finishing or removing a finish from a flat surface, must be performed in courses or parallel paths and if the revolving surface treating member was permitted to tilt down at one end, uneven and scored work would be done. It is the object of the invention to do the work in courses and to do it so perfectly, that the courses may be overlapped without visible effect after the work is completed.

In carrying out the invention a base member is provided a transverse opening intermediate its ends, for receiving a surface treating drum and exposing the underside of the latter to the work. That portion of the base in front of the opening may be termed the "advance" portion and that portion in rear of the opening, may be termed the "following" or "trailing" portion. One of the features resides in providing a shoe on the following portion of less width than the advance portion and also of a width less than the length of the drum; whereby the following portion will always be supported upon worked surface and the chance of being supported partly on worked or sanded surface and partly upon unworked surface, which would tilt the device and cause the drum to cut deeper at one side, is eliminated. The advance portion and the shoe may each have a covering of soft fabric or other suitable material to hold the metal out of contact with the working surface and prevent marring of the latter. These coverings may be suitably fastened so as to be removable.

The invention will be more readily understood from a reading of the following specification and by reference to the accompanying drawings, in which an example of the invention is shown, and wherein:

Figure 1 is an elevation of a surface treating machine equipped with a base constructed in accordance with this invention,

Fig. 2 is a plan view of the base, 65

Fig. 3 is an underside view of the same;

Fig. 4 is a longitudinal sectional view on the line 4—4 of Fig. 2, and

Fig. 5 is a transverse sectional view on the line 5—5 of Fig. 4. 70

In the drawings the numeral 10 designates an elongated base member which I preferably form as a plate with an upstanding marginal flange 11 on its upper side, extending entirely around the plate. At the central portion of the plate a transverse opening or slot 12 is provided. At each end of the slot the flange 11 is built up at 13 and inwardly directed ears 14 are made integral with the portion 13, flange 11 and base plate. 75 These ears receive the lower ends of posts 14' which are fastened therein by set screws 15 or any other means. The manner of attaching the base to the machine is optional and may be changed in accordance with the 80 machine used.

I have shown a frame 16 vertically adjustable in the posts and provided with a motor driven drum 17 which latter projects through the slot 12. The frame and drum 90 form no part of this invention, but are fully shown and described in my application on surface treating machine, filed Feb. 13, 1920, Serial No. 358,485. The drum is rapidly revolved and has a surface covering of 95 sand paper, or polishing cloth or other material according to the class of work to be done. Machines of this character are used in sanding new and old wooden surfaces and also for polishing finished surfaces. 100

The machine is moved in direction of the arrows. The rear or following portion 18 is cut away on each side of a central longitudinal shoe 19 extending from the slot 12 to the rear edge of the plate. This shoe 105 has a width considerably less than the length of the drum 17. The advance portion 20 of the plate, which is that portion lying in advance of the slot, is flush with the under surface of the shoe. A strip of soft fabric 110 21 is employed as a covering for the advance portion and a similar strip 22 is used

to cover the shoe 19. Each strip has one end passed up through the slot 12 and folded back over a transverse rib 23 contiguous to the edge of said slot; while the other end 5 of the strip is folded over the flange 11 at the end of the plate. Transverse fastening bars 24 are pressed against the ends of the cloth by eccentric latches 25 pivoted on studs 26 projecting up from the plate 10. 10 The latches are confined on the studs by nuts 27. By turning the latches the ends of the strips are released and the strips may be removed or tightened. It is obvious that the manner of fastening the ends of the 15 strips permits of great variation.

When the machine is in use the strip 21 of the advance portion 20 is always resting on the treated surface; while the strip 22 of the shoe is resting on the surface which 20 has been treated. By making the strip 22 and shoe 19 narrow so that the ends of the drum project on each side of the said parts and by elevating the portion 18 from the center of the slot 12 rearwardly, all liability 25 of the rear portion of the base resting on an untreated portion of the surface, is obviated. It is obvious that if the surface was being removed to a depth of $\frac{3}{2}$ of an inch and one side of the rear portion 30 rested on uncut surface and the other on cut surface, the drum would be disposed $\frac{3}{2}$ of an inch lower at one end than at the other end, consequently an uneven cut re-

sulting in scores would be had. The advance portion is ample enough to firmly support the machine on the margin of a surface 35 and as the machine is moved forward the drum will be carried onto the edge of the surface. Likewise the shoe is sufficient to support the machine until the work is carried to the opposite edge. By the arrangement 40 the entire surface may be worked.

What I claim, is:

In a machine of the character described, a base having a substantially flat advanced portion and a trailing portion, said base having a transverse opening between said portions, said advanced portion extending for substantially the entire length of the transverse opening, a frame arranged upon 45 and carried by the base, a rotatable surface treating element carried by the frame and projecting into the transverse opening and extending downwardly beyond the opening, means to drive the rotatable surface treating element, and a shoe carried by and depending from the trailing portion, said shoe having its longitudinal edges disposed inwardly for substantial distances from the ends of the rotatable surface treating element 50 so that either longitudinal edge may be conveniently retained out of engagement with the untreated portion of the surface.

In testimony whereof I affix my signature.

ALEX A. CLARKE.
